United States Patent Office

Des. 198,481
Patented June 16, 1964

198,481

BOTTLE CARRIER

Stanley R. Koolnis, Sparta, N.J., assignor to Kapak, Inc.,
New York, N.Y., a corporation of Delaware

Filed Dec. 26, 1963, Ser. No. 77,931

Term of patent 14 years

(Cl. D58—26)

FIG. 2

FIG. 3

FIG. 1 is a perspective view of a bottle carrier, showing my new design;

FIG. 2 is a side elevational view thereof; and

FIG. 3 is a bottom plan view thereof.

I claim:

The ornamental design for a bottle carrier, as shown.
